His attorney.

UNITED STATES PATENT OFFICE.

HOWARD J. MIDDLETON, OF TOLEDO, OHIO, ASSIGNOR OF ONE-HALF TO FRED. W. MANTHEY, OF TOLEDO, OHIO.

CARBURETER.

1,282,271.

Specification of Letters Patent. Patented Oct. 22, 1918.

Application filed September 22, 1916. Serial No. 121,567.

To all whom it may concern:

Be it known that I, HOWARD J. MIDDLETON, a citizen of the United States, and a resident of Toledo, in the county of Lucas and State of Ohio, have invented a certain new and useful Carbureter; and I do hereby declare the following to be a full, clear, and exact description of the invention, such as will enable others skilled in the art to which it appertains to make and use the same, reference being had to the accompanying drawing, and to the characters of reference marked thereon, which form a part of this specification.

This invention relates to carbureters for use in connection with internal combustion engines.

The object of my invention is the provision, in a carbureter, of improved means for controlling the admission of air to the mixing chamber thereof, whereby an increased volume of air is admitted to said chamber when the throttle has been opened a predetermined extent.

The invention is fully described in the following specification, and while, in its broader aspect, it is capable of embodiment in numerous forms, a preferred embodiment thereof is illustrated in the accompanying drawing, the carbureter being shown in central longitudinal section therein.

Referring to the drawing, 1 designates the casing forming the mixing chamber 2, and having its lower end projecting, in the present instance, down through the bowl 3 which forms the float chamber of the carbureter and has its upper end provided with an outlet passage 4 and flanged as at 4^a, to provide a coupling member to adapt it to be secured to the customary manifold of an engine. A throttle valve 5 of butterfly form is mounted in the outlet passage 4 and fixed to a shaft 6 for turning movements therewith. 7 designates a control arm which fixedly projects transversely from one end of the shaft 6 without the casing 1. The casing 1 is flanged adjacent to its middle as at 8 to adapt it to seat over and close the top of the bowl 3 and the lower end of said casing is provided with a tubular extension 9, which is threaded through a central bottom opening in the bowl 3. The lower end of the extension 9 threads without the bowl bottom into a horn 10 and serves to hold said horn firmly to the bottom of the bowl. The horn

10 forms an air intake passage 11, which opens to the atmosphere at the outer end of the horn and communicates at its inner end with the lower end of the extension 9. The portion of the casing 1 which forms the mixing chamber 2 above the extension 9 flares outward from said extension and then inward, to the portion of the casing forming the outlet passage 4.

A fuel nozzle 12 extends upward within the extension 9 centrally thereof and from within the registering portion of the passage 11, being threaded in the bottom wall of said passage, as shown at 13, and having its fuel discharge passage in communication with the bottom of the float chamber through the passage 14 provided in a portion of the horn 10 and through the bottom of the bowl 3. The nozzle 12 has a restricted discharge orifice at its upper end and preferably has its upper end in cup form and flaring outward from the discharge orifice, as shown. The length of the nozzle 12 is preferably such as to dispose its upper end adjacent to or within the lower end portion of the mixing chamber 2.

A choke valve 15 for controlling the air supply to the mixing chamber 2 from the air supply conduit 11 is mounted in the extension 9, having a longitudinally sliding fit therein, being partially guided in its movement by the guide ribs 2^a in the chamber 2. This valve is preferably of a length to extend from the lower end of the extension 9 to a point above the upper discharge end of the nozzle 12 and is provided longitudinally therethrough with a central air passage 16, which is gradually restricted in diameter upward from its lower end to a point at the side of the discharge end of the nozzle, when the valve is in normal lowered position, and thence preferably flared outward, as shown. The restricted portion of the valve passage 16 is slightly larger than the flared end of the nozzle 12 to permit the passage of a small stream of air upward through the valve around the discharge end of the nozzle when the nozzle is within the restricted portion of the valve passage. It will be understood that as the valve is raised from normal position the volume of air passing through the valve is increased in proportion to the increase in the space between the nozzle end and the wall of the valve passage, due to the taper form thereof.

The valve 15 is connected by a rod 17 to the throttle valve 5 at the edge thereof which moves upward when the throttle is opened, thereby causing the throttle valve 5 and air valve 15 to have opening and closing movements in unison.

It is important for economy in fuel consumption and for improved running conditions of a motor to admit an increased volume of air to the mixing chamber when the throttle has been opened a predetermined extent. This is accomplished, in the present instance, by providing the air valve 15 with a plurality of laterally extending ports 18, which open outward from the passage 16 transversely of its axis, and are normally closed at their outer ends by the casing extension 9. These ports are so arranged with respect to the length of the valve and the lower upwardly flaring end of the mixing chamber 2 that they are uncovered to the lower end portion of the mixing chamber when the valve has been raised a predetermined extent, thereby admitting a greater volume of air into the mixing chamber 2 from the air supply passage 11, and is permitted to pass into the chamber 2 through the valve passage 16 around the nozzle. It is evident that the volume of air flowing into the chamber 2 from the ports 18 is determined by the extent of uncovering of said ports. It is preferable to make some of the ports 18 longer than the others lengthwise of the valve so that a greater upward movement of the valve will be permitted before the ports are entirely uncovered.

I wish it understood that my invention is not limited to any specific construction, arrangement, or form of the parts, as it is capable of numerous modifications without departing from the spirit thereof as defined in the claim.

Having thus described my invention, what I claim as new and desire to secure by Letters Patent, is,—

In a carbureter, a casing having an elongated passage therethrough in communication at its lower end with the atmosphere and being conically enlarged and then gradually restricted intermediate its ends to form a mixing chamber, the walls of said chamber being formed with longitudinally extending guide ribs, an air valve fitted in said passage below said chamber and guided by the passage wall and said ribs for longitudinal sliding movements therein, said valve having an air passage longitudinally therethrough which gradually reduces in size from its lower to near its upper end, and also having air discharge ports of varying vertical width extending laterally from said air passage below the portion thereof which is reduced to the greatest extent and adapted to uncover to the lower portion of the mixing chamber when the valve has been raised a predetermined extent, means for controlling the movements of said valve, and a liquid fuel discharging nozzle extending up into said valve passage.

In testimony whereof, I have hereunto signed my name to this specification.

HOWARD J. MIDDLETON.
